YARN RACK

Emil A. G. Raasch, Wauwatosa, Wis.

Application June 24, 1938, Serial No. 215,675

2 Claims. (Cl. 242—134)

My invention relates to the handling of thread, yarn, and similar material and includes among its objects and advantages the provision of an improved rack.

5 An object of my invention is to provide a rack which may be detachably connected with table tops, chair arms, and the like, and in which the rack is adjustable to accommodate one or a plurality of spools supplied with thread, yarn, 10 and the like.

A further object is to provide a rack designed to support a plurality of spools in which means is provided for collecting a large number of threads in closely nested relation from spools 15 which may be arranged in end to end relation.

With these and other objects in view, this invention consists in certain novel features of construction, combination and arrangement of parts to be hereinafter more fully described and 20 claimed.

For a complete understanding of my invention, reference is to be had to the following description and accompanying drawing, in which

25 Figure 1 is a perspective view illustrating my invention applied to a table top;

Figure 2 is a view taken along the line 2—2 of Figure 1 with a portion illustrated in sections for the sake of clearness; and

Figure 3 is a top plan view with a part broken 30 away for the purpose of illustration.

In the embodiment selected to illustrate my invention I make use of arms 1 and 2 which are preferably formed of wire. The wire of each arm is bent to provide a hook 3 shaped to have 35 pinching relation with a table top, arm rest, or the like indicated at 4. Hooks 3 may be encased in rubber tube 5 to prevent marring of the furniture. The free ends of the hooks 3 are bent outwardly, as at 6, to facilitate connection with 40 the supporting structure.

Arm 1 includes a short, right-angular reach 7, while arm 2 includes a relatively long, right-angular reach 8. To the reach 7 I affixedly connect a tube 9 as by welding at 10. Right-angular reach 8 of the arm 2 is slidably supported inside the tube 9. Reach 8 in combination with the tube 9 provides a supporting bar for yarn and thread spools, one of which is indicated at

11. Spool 11 is of relatively large proportion. When small spools are used, a large number may be mounted on the supporting arm comprising the reach 8 and the tube 9. Tube 9 is of such diameter as to fit loosely in the bores of the 5 spools, thus permitting free rotation for unwinding purposes.

Because of the slideable relation between the reach 8 and the tube 9, the arm 2 may be adjusted toward and away from the arm 1 to vary 10 the length of the supporting bar for the spool or spools depending upon the number of spools being used at a given time. In cases where a large number of spools is being employed it is advisable to employ a thread guide for the thread 15 or yarn being unwound. To this end I provide the arm 1 with a wire 12 made secure by welding 13, and bent to provide a reach 14 paralleling the reach 7. The end of the reach 14 is bent to provide an eye 15 through which the thread 20 or yarn may be threaded for collecting purposes.

Because of the eye or thread guide 15, the thread or yarn being unwound takes a definite position determined by the thread guide, thus facilitating unwinding of the material, which is 25 particularly advantageous when unwinding a group of threads. The spools are easily connected with the rack by merely separating the arms 1 and 2.

What is claimed is:

1. A thread or yarn rack comprising a pair of 30 arms, each arm including a hook for detachable connection with a support, each arm including a right-angular reach, a tube fixedly connected to one reach, the other reach being slideable inside 35 said tube, said tube and the said other reach constituting a support for spools, and a thread guide carried by one of said arms.

2. A thread or yarn rack comprising a pair of 40 arms, each arm including a hook for detachable connection with a support, each arm including a right-angular reach, a tube fixedly connected to one reach, the other reach being slideable inside 45 said tube, said tube and the said other reach constituting a support for spools, a thread guide carried by one of said arms, and protective covering encasing said hooks.

EMIL A. G. RAASCH.
